(57) **CLAIM**

The ornamental design for a coffee maker, as shown and described.

DESCRIPTION

FIG. 1 is a front elevational view of a coffee maker showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front right top perspective view thereof; and,

FIG. 8 is a front left top perspective view thereof.

Broken lines shown in the drawings illustrate portions of the coffee maker, and form no part of the claimed design. The dot-dash broken lines shown in FIGS. 1, 5, 7 and 8 define, but are not included in, the boundaries of the claimed design.
